HOLDER FOR KEYS

Anthony Zaccardo, Haverstraw, N. Y.

Application May 19, 1950, Serial No. 163,015

2 Claims. (Cl. 150—37)

1

With the increased use of parking meters in cities and towns, it becomes increasingly important for motorists to have coins to place in the parking meters, and to remember that coins must be put in the parking meters. While a 5 motorist goes into a store to obtain change, his car may be tagged by a policeman for illegal parking; and the motorist is not excused by alleging that he had gone for change to put in the parking meter.

It is an object of this invention to provide a holder for automobile keys and parking meter coins. When a motorist takes the keys out of his car after parking, the holder of this invention serves as a reminder that a coin should be placed in the parking meter, and also provides coins for use in the meter. By replenishing the supply of coins in the holder of this invention from time to time, the owner of the invention never finds himself without change when he 10 needs it for use in a parking meter.

One object of the invention is to provide a holder for keys and parking meter coins with key hooks and a coin pocket correlated in position so as to locate the coins at the region where the keys impart the minimum of thickness to the holder. This result is obtained by having key hooks located at a substantial distance above the coin pocket so that the overlapping heads of the keys are above the portion of the pocket that holds the coins, though the lower portions of the keys extend downward across the pocket and keep the total height of the key and coin holder within the limits of a conventional key case.

Another object of the invention is to provide a folding holder for keys and parking meter coins with a pocket which is accessible through a long slot that extends across a major portion of two panels of the folding holder, and that has a slide fastener for opening and closing the entrance to the coin pocket with the slide fastener extending in such a direction that it does not interfere with the folding of the panels of the holder upon one another.

One feature of the invention relates to a construction which permits the use of a wide pocket extending across more than one panel of the holder with provision for preventing coins from lodging across the fold line when the panels are in an unfolded position. The subsequent folding of the panels would be difficult and inconvenient with a coin located across the line of the fold.

Other objects, features and advantages of the

2

invention will appear or be pointed out as the description proceeds.

In the drawing, forming a part hereof, in which like reference characters indicate corresponding parts in all the views,

Fig. 1 is a view, partly broken away, showing the inside of the key and coin holder of this invention with the panels in the unfolded positions that they occupy when the holder is open,

10 Fig. 2 is a view showing the outside of the key and coin holder of Fig. 1, with the panels in the same unfolded positions as in Fig. 1, and with the coin pocket open throughout a portion of its length,

15 Fig. 3 is a sectional view taken along the line 3—3 of Fig. 2.

The holder of this invention comprises an outside cover 10, preferably made of a single piece of leather, and comprising three panels 11, 12, and 13 that are hinged together along fold lines 15. In the preferred construction the leather is sufficiently flexible so that no scoring or other weakening of the material at the fold lines is necessary.

20 25 There is a slot 17 opening through the cover 10 and extending across the major portion of the panels 12 and 13. This slot 17 extends transversely of the fold line 15 that connects the panels 12 and 13, and preferably extends at right angles to the fold line. The slot is open and closed by a slide fastener of the type which has cooperating fastener elements 20 connected with tapes 21 and 22 that are secured to the holder along the lower and upper edges of the slot.

30 35 The slide fastener elements are brought together and moved apart by a slider 24 which is pulled along the slide fastener by a tab 25. Such slide fasteners are well known in the art and no further description of them is necessary for a complete understanding of this invention.

35 40 There is a lining 27 extending over the entire inner surface of the cover 10 in the illustrated embodiment of the invention. Less extensive lining can be used and in some models of the invention the lining covers only the lower portion of the cover below the slot 17 and to a level just above the slot. The lining 27 is connected with the cover around the side and bottom edges of the lining by a row of stitching 28 so as to form a coin pocket between the cover 10 and the lining 27. The slot 17 provides access to the coin pocket below the slot; and the space between the lining and the cover above the slot, and beyond the end 50 55 of the slot, is cut off from the coin pocket by lines

of stitching 30 and 31 which connect the lining to the cover.

The slot 17 is long enough to provide a wide mouth at the entrance to the coin pocket but it is important to restrict the positions of the coins in the pocket so that they do no extend across the fold 15 between the panels 12 and 13. Coins lodged in a position across the fold would prevent the panels from being folded and would put the user of the invention to the inconvenience of moving the coins about in the pocket until he obtained a clear space along the fold. In the construction illustrated there is a partition formed by a double line of stitching 34 extending upward from the bottom portions of the cover and lining to a region somewhat below the slot 17. It is desirable to have this partition extend far enough up in the pocket so that it separates the coins into the separate compartments of the pocket; but it is also desirable that the stitching 34 does not extend all the way up to the slot 17 because access to the different compartments is much more convenient if the user of the invention can put his finger into either of the compartments from either end of the slot across the space above the upper end of the stitching 34.

Substantial additional strength is obtained at a place where the stitching is subjected to the greatest strain by having the line of stitching 34 a continuation and a branch of the line of stitching that connects the lining to the bottom portion of the cover.

In the manufacture of the invention, the stitching progresses along the bottom portion of the middle panel 12, and the cover and lining are turned at right angles when the stitching reaches the fold line 15 that joins the panels 12 and 13. The stitching continues up the fold line making the line of stitching indicated by the reference character 34; and when the line stitching 34 has reached a level somewhat less than one-half way up to the slot 17, the cover and lining are turned about the needle through an angle of 180° so that as the stitching continues it comes back to the bottom portion of the lining and cover leaving a double stitching along the line 34. The lining and cover are then turned 90° to permit the stitching to continue along the bottom of the panel 13. With this procedure, the stitching 34 is a continuous thread with the line of stitching along the bottom of the holder and this adds further to the strength of the connection provided by the stitching 34.

The tapes 21 and 22 are preferably glued to the cover 10 along the lower and upper edges of the slot 17 before being secured in place by stitching. The lower tape 21 is then stitched to the cover 10, and only to the cover 10, by a line of stitching 36. The lining 27 is then applied to the inside surface of the cover and the upper tape 22 is secured to both the cover and the lining 27 by a row of stitching 30 which also fastens the lining to the cover and prevents coins in the coin pocket from getting between the cover and the lining at locations above the slot 17 where it would be difficult to reach the coins and where they would increase the thickness of the holder at a region where the overlapping heads of keys in the holder give the key assembly its maximum thickness.

At the upper end of the panel 12 there is a metal bracket 40 having slots 41 into which there are inserted the heads of key hooks 44 which hang down from the bracket 40 over the face of the lining 27. The bracket 40 is located over the

lining 27 when the invention is made with the lining extending over the entire inner surface of the cover 10. Fastening means, preferably hollow rivets 46, extend through both the lining 27 and the cover 10 for securing the bracket 40 in place.

When the invention is in use, keys 48 are put on the hooks 44 and hang down across the slot 17 and across at least a portion of the coin pocket, but the keys are separated from the slot 17, the slide fastener and the coins, by the lining 27 which forms one wall of the coin pocket.

When the holder is folded, the panel 13 is hinged over panel 12 so as to cover the bracket 40, hooks 44 and keys 48. Panel 11 is then folded over across the outside of the panel 13, and a socket element 51 of a snap fastener secured to the panel 11 engages a ball element 52 secured to the panel 13 and comprising the complementary portion of the snap fastener. The holder is kept closed by this snap fastener 51-52, and any particular key that is to be used while the holder is closed must be swung upward about the bracket 40 before the panels are folded in on one another.

In the region of the hooks 44, where the head portions of the keys overlap one another, the keys have their maximum effect in increasing the thickness of the holder. It is a feature of the invention that the region where the key assembly has its maximum thickness is located above the coin pocket so that when there are coins in the pocket, only the lower portion of the holder will have its thickness increased by the coins. Because of this correlation, the holder of this invention, even though it has a substantial number of five cent and one cent pieces in its coin pockets is not any more bulky or thicker than the conventional key case, the difference being merely that the thickness of the holder of this invention extends throughout substantially the entire height of the holder whereas conventional key cases have a non-uniform thickness with the region of greatest thickness located near the upper ends of the keys.

Fig. 3 shows the way in which a coin 55 can be pulled up in the pocket by a finger 56 inserted into the coin pocket through the slot 17. The leather of the cover 10 is sufficiently flexible to pull outward so that a coin can be pulled out of the pocket in the manner illustrated in Fig. 3.

The preferred construction of the invention has been illustrated and described, but changes and modifications can be made and some features of the invention can be used alone and in different combinations without departing from the invention as defined in the claims.

I claim as my invention:

1. In a conventional key case including a flexible sheet having a plurality of panels, at least one of which folds over another to close the case, a plurality of key hooks connected to one of the panels at its upper end and extending transversely of the line along which the panels fold, the improvement comprising a lining covering the inside of at least part of at least one of the panels, the panel having the lining being slotted along a portion of its area over the lining to provide access to the space between the lining and the panel over which the lining extends, and releasable fastening means that hold the slot closed.

2. The key case described in claim 1, and in which the slot is located near one edge of the lining, and a slide fastener is connected to the panel from opposite sides of the slot for closing the slot, and stitching extends through the panel

and along the edges of the lining to secure the lining to the panel, the stitching along one edge of the lining also securing one side of the slide fastener to the panel.
